UNITED STATES PATENT OFFICE.

ALBERT DUIS, OF STREATOR, ILLINOIS.

GAS-WASHER FOR ACETYLENE-GENERATORS.

1,108,978.

Specification of Letters Patent.

Patented Sept. 1, 1914.

Application filed March 21, 1914. Serial No. 826,284.

To all whom it may concern:

Be it known that I, ALBERT DUIS, a citizen of the United States, residing at Streator, in the county of La Salle and State of Illinois, have invented a new and useful Gas-Washer for Acetylene-Generators, of which the following is a specification.

The present invention relates to improvements in gas washers for acetylene gas generators, being designed for use in conjunction with the construction shown in my U. S. Letters Patent No. 1,088,064 dated February 24, 1914, one object of the present invention being the provision of means for taking care of the condensation in the gas, either before its point of delivery to the outlet and also at a point adjacent the introduction to the outlet, and for also washing the gas before the delivery thereof to the means for taking care of the condensation, so as to reduce the moisture in the gas and to deliver to the outlet, the dry gas.

A further object of the present invention is the provision of means whereby the condensation is removed by a suction pump and without disturbing the generator.

A still further object of the invention, is the provision of a gas washing receptacle 30 adapted to be interposed between the generating compartment of generator and the main carbid holder and to form a support therebetween, said washer being so constructed that the gas is admitted at one 35 point of the generator and caused to pass through the body of washing water before the introduction thereof to the pipes that deliver the dry gas to the outlet.

With the foregoing and other objects in view which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

In the drawings Figure 1 is a vertical 50 central view through the generator, the lower portion of which is not shown. Fig. 2 is a side elevation of the pipes used in connection with the condensation receiving means. Fig. 3 is a top plan view of the 55 gas washer *per se*. Fig. 4 is a section taken on line 4-4 of Fig. 3.

Referring to the drawings, the numeral 1 designates a frusto-conical generator which with the outer cylindrical casing 2 is connected to form a water tight joint and 60 provides a concentric sealing chamber 3. Removably mounted upon the upper end or rim of the member 1 is a gas washing member 5, which is made in the form of a hollow ring, the same being provided with 65 the inlet or filling spout 6 to its chamber 7. A gas inlet pipe 8 is carried by the member 5 and opens at a point above the water within the chamber 7 and below the deflector 9, which is so disposed as to cause the gas 70 to pass downwardly into the water in the direction of the arrows as shown in Fig. 1, whereby any of the impurities are washed out of the gas before the delivery of such gas into the outlet pipes 13 and 14. The 75 pipe 13 is carried fixedly by the washing member 5 and fits telescopically over the upper end of the pipe 14.

The carbid holder 10 is fitted so that its rim 11 surrounds the upper end of the gas 80 washing member 5 and surrounding the upper end of the member 1 and also the carbid receptacle is a bell 12, whose apron portion fits within the sealing compartment below the water therein. A carbid feeding mechanism G is provided for feeding carbid from the carbid holder to the generating chamber. It will thus be seen that the gas generated by the carbid falling into the water within the member 1, will cause the bell to elevate, 90 holding the same buoyantly, as is the usual custom, the outlet of such gas being through the pipe 8 of the chamber 7 of the member 5 and the directing pipes 13 and 14. The lower end of the pipe 14 is mounted at 15 95 through the wall of the member 1 and enters the coupling 16, from which leads upwardly, the vertical pipe 17, which when the parts are assembled as in Fig. 1, is disposed exteriorly of the bell 12 within the casing 2, 100 the pipe 20 being disposed through the wall of the casing 2 and led to the outlet (not shown). A valve 18 is connected in the pipe 17 and led from the valve 18 is a union connection 19 so that the parts may be readily connected and disconnected, and also so that the valve 18 may be closed to permit of the removal of the condensate, as will presently appear.

In order to provide a means for receiving 110 the condensate from the gas, as it enters the coupling 16 from the pipe 15, a pipe 21 is

connected to the lower portion of the coupling 16 and has the return member 22 connected thereto and to the pipe 23, a smaller pipe 24 having its end disposed within the pipe 23, extends upwardly to a point adjacent the cover C of the member 2, so that said cap 25 may be removed and a suction pipe attached thereto to drain the condensate from the pipes 21 and 24 and the return member 22. To further safeguard the gas, so that any condensate may be prevented from entering the outlet pipe 20, a pipe 26 is connected to the union coupling member 19 at a point adjacent the connection of the pipe 20 thereto, and such pipe enters the sealing compartment 3 below the upper surface of the water, so that any condensate will run down such pipe into the water in the sealing compartment.

From the foregoing description, taken in connection with the drawings, it is evident that with a generator constructed according to the present invention, that the water of condensation will be thoroughly removed from the gas before the passage thereof through the pipe 20, and that by means of the pipe 24 and the cap 25, a suction pump

may be connected to the pipe 24 and thus draw the condensate from the member 22 and the pipes 21 and 23 without disturbing the generator or draining the gas therefrom.

What is claimed is:

An acetylene gas generator, including a generating chamber open at the upper end, an annular gas washing member fitting upon the upper end thereof, a carbide holder supported by the gas washing chamber, means for feeding carbide from the carbide holder to the generating chamber, a pipe leading from the gas washing member exteriorly of the generating chamber, a U-shaped condensate receiving member into which said pipe empties, a draining pipe connected to one terminal of said condensate member, and a gas directing conduit leading from the other terminal of the U-shaped member.

In testimony that I claim the foregoing as my own, I have hereto affixed my signature in the presence of two witnesses.

ALBERT DUIS.
